Fig. 5

To all whom it may concern:

Be it known that I, Frederick W. Hertzler, have invented a new, original, and ornamental Design for a Camera, of which the following is a specification, reference being had to the accompanying drawing, forming a part hereof.

Figure 1 is a front elevational view of a camera, showing my new design;

Figure 2 is a top plan view;

Figure 3 is a rear elevational view;

Figure 4 is a side elevational view as viewed from the left side of Figure 1; and

Figure 5 is a side elevational view as viewed from the right side of Figure 1.

The dominant features of my design are shown in solid lines.

I claim:

The ornamental design for a camera, as shown and described.
